209,479

PACKAGING TRAY FOR SMALL CYLINDRICAL ARTICLES OR THE LIKE

Willard G. Cutler, Holyoke, Mass., assignor to The Electric Game Company, Holyoke, Mass., a corporation of Massachusetts

Filed May 23, 1966, Ser. No. 2,399

Term of patent 14 years

(Cl. D58—13)

FIG.1

FIG.2

FIGURE 1 is a perspective view of a packaging tray for small cylindrical articles or the like showing my new design;

FIGURE 2 is side view thereof partially in section. The bottom of the tray is a reverse of the top.

I claim:

The ornamental design for a packaging tray for small cylindrical articles or the like, substantially as shown and described.

References Cited

UNITED STATES PATENTS

D. 190,974	7/1961	Salis	-----	D58—13
D. 199,765	12/1964	Weiss	-----	D58—13
3,176,838	4/1965	Duval.

EDWIN H. HUNTER, Primary Examiner.

BRUCE W. DUNKINS, Examiner.

WINIFRED E. HERRMANN, Assistant Examiner.